UNITED STATES PATENT OFFICE.

FRANKLIN RUDOLPH AND EDWARD W. CARNES, OF CHICAGO, ILLINOIS, ASSIGNORS TO AMERICAN CAN COMPANY, OF NEW YORK, N. Y., A CORPORATION OF NEW JERSEY.

TIN-PLATE-SHIPPING PACKAGE OR HOLDER.

1,150,455.

Specification of Letters Patent. Patented Aug. 17, 1915.

Application filed November 11, 1907. Serial No. 401,540.

To all whom it may concern:

Be it known that we, FRANKLIN RUDOLPH and EDWARD W. CARNES, citizens of the United States, residing in Chicago, in the 5 county of Cook and State of Illinois, have invented a new and useful Improvement in Tin-Plate-Shipping Packages or Holders, of which the following is a specification.

Our invention relates to improvements in 10 shipping packages for tin plate.

The object of our invention is to provide a package or holder for shipment of tin plate in the customary sized packages or bundles, of say about 100 pounds weight and 15 112 sheets, which will be of a strong, simple and durable construction; which may be readily and conveniently applied; which will efficiently bind the numerous thin sheets of the package together so that they will 20 mutually reinforce and strengthen each other as well as the package or holder itself; which will effectively protect the corners and edges of the sheets in the package from denting, bending or other injury; which will 25 properly protect the outer surfaces of the upper and lower sheets from wet, dirt, scratching, marring or other injury: and which at the same time will be a returnable package or holder and capable of being used 30 over and over again.

Our invention consists in a shipping holder for piles or packages of tin plate, comprising a plurality of flanged or channeled binding strips of heavy sheet metal, 35 preferably galvanized sheet steel, or other suitable metal, fitting over and embracing the edges of the pile or package of tin plate sheets, and provided with interengaging fastening devices at their meeting ends the 40 corners of the package, the fastening devices preferably consisting of a slot on one member and a bendable lip or tongue on the other member passing through such slot, and clenched down to bind the parts together.

It further consists, in connection with these parts, of upper and lower protecting sheets of paper, paper-board, wood veneer, thin sheet metal, such as taggers iron, or other 50 suitable material, embraced within the flanges of the channel strips to protect the outer surfaces of the upper and lower sheets of tin plate.

It further consists, in connection with 55 these parts, of one or more intermediate

binding strips furnished with an interengaging slot and tongue at its meeting ends and embracing the channel binding strips at the sides of the package.

It further consists in the novel construction of parts and devices and novel combinations of parts and devices herein shown and described.

In the accompanying drawing, forming a part of this specification, Figure 1 is a perspective view of a tin plate shipping package or holder embodying our invention; Fig. 2 is a vertical section on line 2—2 of Fig. 1; Fig. 3 is a detail horizontal section on line 3—3 of Fig. 1; Fig. 4 is a detail perspective 70 view of one of the end binding strips; Fig. 5 is a perspective view of one of the flanged or channeled side binding strips; Fig. 6 illustrates a modification in which two of the binding strips are made integral with 75 each other; and Fig. 7 illustrates a modification in which three of the binding strips are made integral with each other.

In the drawing A represents a shipping unit or package of tin plate or other thin sheet metal, ordinarily of about 100 pounds weight, and comprising about 112 sheets, a, of say 14 by 20 inches, or other customary dimensions. Our holder for the shipping unit or package A of sheets a, comprises a 80 plurality of flanged or channeled side and end binding strips B B¹, the flanges b of which overlap and embrace the upper and lower edges of the shipping unit or package A at the sides and ends of the package; and C C are upper and lower protecting sheets for the shipping unit or package A, preferably of water-proofed paper board or other suitable material and embraced within the flanges of the binding strips B. The 85 binding strips B whether made in two, three or four separate pieces, are furnished at their meeting ends, one with an integral tongue b¹ and the other with a slot b² through which the tongue b¹ is inserted, and 90 then the tongue b¹ is bent or clenched down around the corner of the package at the meeting ends of two binding strips. The binding strips are also preferably furnished at the slot-end thereof with a projecting lip or flange b³ which is bent around the corner of the package to reinforce the corner and aid in securing the meeting ends of separate 95 binding strips together. D is an intermediate binding strip; preferably of sheet 100

105

110

metal, and furnished at one end with a slot d and at its opposite end with a tongue d' which is inserted through the slot and clenched down so as to cause the intermediate binding strip to firmly embrace the package and reinforce the flanged or channeled binding strips B B at their middle portion. Any desired number of intermediate binding strips may be employed.

- 10 In the modification illustrated in Fig. 6 the channeled binding strips are made in two separate pieces, as illustrated in Figs. 1 to 4; that is to say, one of the end binding strips B^1 is made integral with one of the side binding strips B . This construction reduces the number of detachable interengaging attaching devices b^1 b^2 b^3 employed for the meeting ends of the binding strips at the corners of the package.
- 15 20 In the modification illustrated in Fig. 7 the two side binding strips B B and one of the end binding strips B^1 , are all three made in one integral piece. We prefer to employ the construction illustrated in Figs. 1 to 4, wherein each of the channeled binding strips B B , B^1 is in a separate piece, as in this construction the binding strips when removed from the package of tin plate are in more convenient form for return shipment.
- 25 30 We claim:

1. A holder for shipment of packages of tin plate, comprising a plurality of detachable, separate piece, channel-shaped, heavy sheet metal binding strips, each having upper and lower inwardly extended flanges and adapted to be connected together to form a rigid, rectangular, frame-like holder having a continuous rectangular inwardly facing channel formed by said flanges and adapted to receive the edges of the package, said strips being furnished at their meeting ends with interengaging slot and tongue de-

vices for detachably securing the same together at a plurality of corners of the package, the flanges of one pair of said binding strips fitting within and being embraced by the flanges of another pair of said binding strips at the meeting ends thereof, and each of said binding strips having a projecting member at its end bent at right angles thereto and embracing the adjacent binding strip, substantially as specified.

2. A holder for shipment of packages of tin plate, comprising a plurality of detachable, separate piece, channel-shaped, heavy sheet metal binding strips, each having upper and lower inwardly extended flanges and adapted to be connected together to form a rigid, rectangular, frame-like holder having a continuous rectangular inwardly facing channel formed by said flanges and adapted to receive the edges of the package, said strips being furnished at their meeting ends with interengaging slot and tongue devices for detachably securing the same together at a plurality of corners of the package, the flanges of one pair of said binding strips fitting within and being embraced by the flanges of another pair of said binding strips at the meeting ends thereof, and each of said binding strips having a projecting member at its end bent at right angles thereto and embracing the adjacent binding strip, substantially as specified.

FRANKLIN RUDOLPH.
EDWARD W. CARNES.
